(57) **CLAIM**

The ornamental design for an enclosure for capture devices, as shown and described.

DESCRIPTION

FIG. 1 is a perspective view of an enclosure for capture devices showing my new design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings illustrating unclaimed portions of the enclosure for capture devices form no part of the claimed design.
